UNITED STATES PATENT OFFICE.

JOHN T. KIRK, OF NEW BEDFORD, MASSACHUSETTS, ASSIGNOR TO DRAPER CORPORATION, OF HOPEDALE, MASSACHUSETTS, A CORPORATION OF MAINE.

FILLING-REPLENISHING LOOM.

Application filed January 18, 1926. Serial No. 81,953.

This invention relates to filling replenishing looms and is more particularly directed to means for preventing displacement of the yarn on the filling carriers while in the hopper.

The yarn which is to be used in the loom as filling or weft is now usually wound upon the filling carriers or bobbins in conical layers or "weft wind". During weaving, such filling carriers or bobbins thus wound with filling are supported in a hopper and are successively presented to transferring position for transfer to the shuttle.

During the weaving operation, the ends of filling are now usually secured to some fixed point, preferably connected to the hopper. The tendency, therefore, is for the end windings of yarn along the filling carriers to slough or to become displaced on the filling carriers. This condition is particularly observable in connection with some kinds or character of yarn, such, for instance, as silk, artificial silk or the like. Should the yarn thus slough or become displaced about the end or tip portion of the bobbin or filling carrier, the filling is liable to become broken when the carrier is transferred to the shuttle, or, if not broken then, the shuttle may fail to thread on the first pick following replenishment, or the yarn may come from the end of the filling carrier or bobbin several windings at a time; thus bunching up and becoming entangled, with consequent defect in the weaving operation.

This displacement of the yarn on the filling carriers while in the hopper becomes a source of difficulty when weaving with silk or artificial silk or even some fine yarns of other fibrous character, and is generally referred to technically as sloughing. This term, therefore, when hereinafter used, is intended to mean the displacement, particularly of the end windings on a filling carrier or bobbin, such displacement usually manifesting itself in coils of filling moving from the end windings longitudinally along the filling carrier or bobbin towards the tip end thereof.

The object of the present invention is to provide means of simple and effective character that shall effectively prevent sloughing or displacement of the yarn on the filling carriers while in the hopper, and, in accordance with one form of the present

invention, a filling carrier in the hopper has bearing upon the end windings thereof, means that act to prevent the end windings from sloughing or displacement on the filling carrier. One good form of means to this end comprises a pad of suitable material that shall bear upon the end windings of the filling carrier while in the hopper, prevent sloughing or displacement of the yarn thereon, and yet not interfere with the support of the filling carrier in the hopper or its transfer to the shuttle.

The invention, novel features thereof, and new combination of parts, will best be made clear from the following description and the accompanying drawings of one good form thereof.

In the drawings:

Fig. 1 is a perspective view at the replenishing side of the loom, showing a hopper containing the present invention;

Fig. 2 is an enlarged sectional detail showing one form of the present invention;

Fig. 3 is an enlarged end view of a hopper having the present invention associated therewith; and

Fig. 4 is a view similar to that of Fig. 3, showing a slightly modified means for supporting the anti-sloughing pad.

The invention shown in the present instance thereof is associated with a rotary hopper, and the advantages of the invention are more particularly manifested in this connection, although it may be employed with other forms of hoppers.

The loom frame 1, Fig. 1, has mounted thereon the hopper stand 2, having the usual cover plate 3 at one end, and mounted on the hopper stand 2 is the stud or dead shaft 4 on which is the rotary hopper. It is usual in the rotary hopper type of filling replenishing hoppers to provide a head for supporting one end of the filling carriers or bobbins, and an opposite head for supporting the other end of the filling carriers or bobbins, and in so far as the present invention is concerned, such supports for the filling carriers or bobbins may be of any desired construction or type.

In the present instance of the invention, the rotary head 5 of the hopper is provided with sockets 6 for supporting the head portions 7 of the filling carriers or bobbins 8, and an opposite or tip end support for the

filling carriers is formed as a disk 9 which may, as may also the head 5, be mounted upon the stud or dead shaft 4 for rotary movement, in order to transfer the filling carriers to transferring position.

The rotary hopper is usually provided with a guiding disk 10 which may be provided with notches 11 for the ends *a* of the filling which leads from the end of the 10 filling carriers in the hopper to a fixed point, preferably in axial alinement with the stud or dead shaft 4 outside of the disk 10. All of these matters, however, are not new, and since they are very well understood by those skilled in the art, further 15 showing and description thereof seems unnecessary.

As indicated in Fig. 2, the disk 9 has a series of openings 12 in which are mounted 20 the tip supports 13, each of which may have a jaw portion 14, as usual, to engage a shoulder or flange 15 formed on or made as part of the disk 9. Each of the tip supports 13 is normally under the influence of a 25 spring, such, for instance, as 16, Fig. 2, normally moving the tip supports towards the tip end portions of the bobbins when they are in the hopper. Each of the tip supports 13 has a rounded seat 17 for the tip portion 30 of the bobbin to be supported by it.

The particular details of the disk 9 and the tip supports are not of the present invention and the brief description thus far given will be sufficient to enable those 35 skilled in the art to understand the invention which is now to be described.

In accordance with the present invention, means are provided to retard sloughing or 40 displacement of the end windings of the yarn on the filling carriers or bobbins while in the hopper, and such means is preferably formed as a pad of some soft material, such as fabric or felt or the like, which 45 will bear upon the windings of filling on a filling carrier while in the hopper.

The invention may take various forms, such, for instance, that there may be a series 50 of pads, one for each filling carrier in the hopper, or, if desired, in some instances, a ring form of pad may be employed to bear against the end windings of filling carriers in the hopper, but in any case, the end windings of a filling carrier in a hopper will be 55 prevented from displacement or sloughing endwise of the filling carrier, so that when transfer takes place no entanglement or breakage of yarn may occur due to such displacement.

In the form of the invention, as shown 60 in Fig. 2, each tip holder 13 is provided with a separate pad 19 which is mounted upon a support attached to the tip holder, and as the pad should bear upon the end windings, preferably by a yielding pressure 65 when the filling carrier is held in the hop-

per, the support is formed as a leaf spring 18, the leg portion 20 of which is secured to the adjacent tip holder 13 by suitable means, such as the screws 21, and at its upper portion the leg 20 is bent laterally and 70 then reversely at 22 to form a seat 23 to which the individual pad 19 is secured to bear upon the end windings of the filling a wound upon the filling carrier 8.

In Figs. 1, 3 and 4 the "anti-sloughing" 75 pad is formed as a continuous ring 24 which may be supported in appropriate manner upon the hopper. As indicated in Fig. 3, each of the tip holders 13 is provided with the spring supports, as described in connection with Fig. 2, but instead of mounting a separate pad 19 on each of the separate spring supports 18, a continuous ring 80 of the pad material 24 is secured upon the seats 23 of the spring supports, substantially as indicated in Figs. 1, 2 and 3. In either event, however, the pad material bears upon the end windings of filling wound upon the filling carrier, and when a filling carrier is in its transferring position, as indicated in Fig. 1, the pad is above the tip end portion of the filling carrier and does not interfere with the free transfer of the filling carrier to the shuttle.

The essentials of the present invention 95 do not require that the "anti-sloughing" pad shall be supported in any particular manner in a hopper or on a hopper, but that it shall be so supported that it will bear upon the end windings of filling carriers or bobbins in the hopper and prevent sloughing or displacement of the yarn thereon while the filling carrier is in the hopper. Preferably, however, the pad (whether it be 100 formed of a single circular member, as 24, or of individual members, as 19 in Fig. 2) will be yieldingly supported, and the yielding supporting means may take various forms, as, for instance, that shown and described in Figs. 2 and 3, although this may 110 be varied.

One variation of the yielding supporting means for the pad is indicated in Fig. 4, wherein the spring supporting means 25 for the pad is directly secured to the head 9 by 115 means such as the screws 26, in which respect the supports 25 differ from the spring supports 18, where they are secured to the tip holders. In other respects, the spring supports 25 may be substantially the same 120 as those previously described in respect to Fig. 2. Where the spring supports 25 are connected directly to the tip disk 9, as indicated in Fig. 4, there will, of course, be a series of these and a continuous pad 24, 125 which may be the same as in Fig. 1, will be secured to the series of spring supports 25. In such case, also, it will be noted, as indicated in Fig. 4, that where a continuous pad bears upon the end windings of filling, 130

as at 27, Fig. 4, the pad will take a natural concave position between the several pad supports 25.

As indicated in Fig. 1, the hopper has 5 associated with it a transerrer 28 which is mounted, as usual, in the stud shaft 29 and has the depending leg 30 to which is pivotally connected the dog 31, as usual. Extending laterally from the transerrer 28 is the 10 arm 32 carrying a bunter member 33 which may act upon the filling carriers at one side edge of the pad, so that the pad does not obstruct the filling replenishing operation.

From the constructions described as good 15 practical forms of the invention, it will be apparent that while the filling carriers having filling wound thereon are in the hopper and subjected to the vibrations of the loom, a pad bears against the end windings at 20 the cone portions thereof at the tip of the filling carriers to prevent sloughing or displacement of the yarn longitudinally of the filling carriers, and while the invention is more particularly advantageous in connection 25 with silk, artificial silk and such character of yarn, it is obvious that it may be employed in connection with filling carriers having any kind of yarn thereon.

What is claimed is:

1. In a filling replenishing loom, the combination of a hopper for filling carriers having filling wound thereon, and supports on the hopper for engaging the end portions of the filling carriers, and means between the end supports bearing upon the conical end windings of filling on a filling carrier while in the hopper to prevent sloughing or displacement of the yarn on the carrier.

2. In a filling replenishing loom, the combination of a hopper having supports for filling carriers to be transferred, and means bearing upon the conical end windings of the filling on a filling carrier to prevent sloughing or displacement of the yarn on the carrier while in the hopper.

3. In a filling replenishing loom, the combination of a hopper having supports for filling carriers to be transferred, and a pad bearing upon the mass of wound filling on a filling carrier to prevent sloughing or displacement of the mass of yarn on a filling carrier while supported in the hopper.

4. In a filling replenishing loom, the combination of a hopper for supporting filling carriers to be transferred, and a yieldingly mounted pad bearing upon the conical end windings of the filling on a carrier to pre-

vent sloughing or displacement of the yarn on the filling carrier while in the hopper.

5. In a filling replenishing loom, the combination of a rotary hopper having end supports for filling carriers, a pad mounted on the rotary hopper for movement therewith and bearing upon the end windings of the filling on a carrier while in the hopper to prevent sloughing or displacement of the yarn on the filling carrier.

6. In a filling replenishing loom, the combination of a rotary hopper for supporting filling carriers to be transferred, means carried by the rotary hopper bearing upon the mass of end windings of a filling carrier in the hopper to prevent endwise displacement of the wound filling, and a support for said means.

7. In a filling replenishing loom, the combination of a hopper for supporting filling carriers to be transferred, means bearing upon the conical end windings of a filling carrier in the hopper to prevent endwise displacement of the wound filling from the conical windings, and a yielding support for said means.

8. In a filling replenishing loom, the combination of a hopper for filling carriers to be transferred, a pad bearing upon the end windings of the filling on a carrier as the carrier is moved to transferring position to prevent sloughing or displacement of the end windings, and a yielding support for the pad acting to hold the latter against the wound filling while the carrier is in the hopper.

9. In a filling replenishing loom, the combination of a rotary hopper having supports for filling carriers, a pad connected to the rotary hopper and bearing downwardly upon the end windings on a filling carrier when in transferring position to prevent sloughing or displacement of the end windings on the filling carrier.

10. In a filling replenishing loom, the combination of a rotary hopper having supports for filling carriers to be transferred, a pad mounted on the rotary hopper radially within the series of filling carriers supported by the hopper and bearing yieldingly upon the end windings of the filling on a filling carrier to prevent sloughing or displacement of the yarn on the filling carrier while in the hopper.

In testimony whereof, I have signed my name to this specification.

JOHN T. KIRK.
